UNITED STATES PATENT OFFICE.

ROBERT L. MARGOLYES, OF NEW YORK, N. Y.

UNION GARMENT.

1,126,541.

Specification of Letters Patent.

Patented Jan. 26, 1915.

Application filed September 25, 1913. Serial No. 791,773.

To all whom it may concern:

Be it known that I, ROBERT L. MARGOLYES, a citizen of the United States, and a resident of New York, borough of Manhattan, 5 county and State of New York, have invented a new and Improved Union Garment, of which the following is a full, clear, and exact description.

My invention relates to garments known 10 as union-suits, and the object thereof is to provide a suit having an opening in the rear for obvious purposes, the body of the garment adjacent the opening being adapted to yield laterally to obviate the necessity 15 of pulling different parts of the garment trying to enlarge the said opening when in need of using the same.

I obtain the above object by providing a bifurcated garment in the rear portion of 20 which I provide a gusset of elastic material so positioned as to increase the size of the opening in the rear of the garment when necessary.

The invention consists of the construction 25 and combination of parts to be more fully described hereinafter and fully set forth in the claims.

Reference is to be had to the accompanying drawings forming a part of this specification, in which like characters indicate corresponding parts in all the views and in which:

Figure 1 is a rear elevation of an embodiment of my invention showing the rear 35 opening closed; Fig. 2 is a similar view showing the rear opening open and showing the location of the elastic gusset forming part of the wedge-shaped member secured in the crotch of the rear blank and custom- 40 ary to most bifurcated garments; and Fig. 3 is a plan view of the wedge-shaped member with the gusset secured thereto.

Referring to the drawings, 5 represents the front blank of a suit and 6, the rear 45 blank of the same. The two blanks are similar with the exception that the rear blank 6 is provided with a waist band 7 formed preferably of elastic material and also with a cut-out or slit 8 into which is 50 fitted a wedge-shaped member 9 having preferably the shape shown in Fig. 3. The wedge-shaped member 9 is secured with the edge a—e to one side of the cut-out of the rear blank 6. The opposite edge e—c re- 55 mains unsecured to the other side of the cut-out and forms a rear opening. The base

edge a—c, is arcuated and forms a continuation of the edge of the rear blank, which is secured, as the other edges of the rear blank, to the edges of the front blank. The wedge portion 9 positioned in the cut-out 60 of the rear blank 6 is wider adjacent its base, thus giving more room at this portion of the garment.

The opening e—c—d formed by the wedge-shaped member 9 and the edge of the cut-out of the rear blank is made to dilate by providing in the wedge portion 9 a member 10 made of elastic material, preferably Jersey, and forming part of the wedge portion adjacent the base of the same, as shown in Fig. 3 by the letters b—c—d. The edge b—c of the gusset forms the continuation of the edge a—b of the wedge portion 9 and is secured to the edge of the front blank 75 5 similar to the manner in which the edge a—b is secured. It could be said that the rear blank 6 is provided with an elastic member adjacent its opening, as in reality the wedge portion 9 is of the same material as 80 the rear blank. This member 10 permits a lateral yielding of the rear portion of the garment, thereby permitting the broadening of the opening formed by the unsecured edges of the wedge member 9 and the rear 85 blank 6.

It is understood that the size and shape of the member 10 can be varied without in any way departing from the spirit of the invention.

Having thus described my invention, I claim as new and desire to secure by Letters Patent:

1. A union suit comprising,—a front blank, a rear blank having a cut-out, and a wedge-shaped member having an arcuated edge, said blanks and member being of non-elastic material, one straight edge of said wedge-shaped member and one edge of the cut-out forming an opening, the other straight edge of said wedge-shaped member being secured to the other edge of the cut-out, the arcuated edge of said wedge-shaped member being secured to the front blank, said wedge-shaped member having an elastic portion adjacent the opening formed by the straight edge of said wedge-shaped member and a cut-out in the rear blank.

2. A union suit comprising,—a front blank, a rear blank having a cut-out, and a wedge-shaped member having an arcuated

edge, said blanks and member being of non-
elastic material, said wedge having an elas-
tic portion at the arcuated edge, said
wedge-shaped member having one straight
edge thereof secured to one edge of the cut-
out in the rear blank, the other edge of the
cut out, with the other straight edge of the
wedge-shaped member forming an opening,
the arcuated edge of said wedge-shaped
member being secured to the front blank,

whereby said elastic portion at the arcuated
edge is also secured to the front blank.

In testimony whereof I have signed my
name to this specification in the presence of
two subscribing witnesses.

ROBERT L. MARGOLYES.
